UNITED STATES PATENT OFFICE

CLAUD A. HENDRICKSON, OF DENVER, COLORADO

VENTILATING FAN

Application filed April 12, 1929. Serial No. 354,554.

This invention relates to improvements in ventilating fans of the type employed for expelling air from buildings and for circulating air for the purpose of heating and ventilating.

It is the object of this invention to produce a fan of the type above mentioned which shall have a large capacity and a high efficiency.

- 10 It is a further object of this invention to provide means for mounting the motor which will prevent the noises produced by the roller bearings from being transmitted to the support and magnified.
- 15 Another object of this invention is to produce a fan construction which shall prevent to as great an extent as practicable a slippage of air about and through the propeller when the same is operating.

- 20 The above and other objects which will become apparent as the description proceeds are attained by means of a construction and an arrangement of parts which will now be described in detail and reference for 25 this purpose will be had to the accompanying drawings in which the preferred embodiment of the invention has been illustrated and in which:

Fig. 1 is a side elevation of the fan looking in the direction of arrow 1, in Fig. 2;

Fig. 2 is a section taken on line 2—2, Fig. 1;

Fig. 3 is a side elevation of a portion of the fan;

35 Fig. 4 is a view looking in the direction of arrow 4, Fig. 2;

Fig. 5 is a side elevation showing one end of a fan blade, looking in the direction of arrow 5 in Fig. 3; and

40 Fig. 6 is a section taken on line 6—6, Fig. 5.

In the drawings numeral 1 represents the circular ring portion of the frame in which the motor 2 is mounted. This frame is provided with three radial arms 3 whose inner ends terminate in a ring 4. These arms are curved outwardly so as to be spaced from the plane of the ring in the manner shown quite clearly in Fig. 2. In the example illustrated the motor is of the circular type and

has secured to it a split ring 5 that is provided with outwardly extending lugs or ears 6 which are perforated for the reception of a clamping bolt 7 in the manner shown in Fig. 4. A sheet of rubber, felt or other resilient material is placed between the outer surface of the motor and the inner surface of ring 5 so as to provide a layer of material that will not transmit sound vibrations from the motor to the ring. In the drawings, the material 8 has been shown as constituting a complete ring but it is possible to have several sections of this material spaced apart if any advantage should be found in this construction. The ring 5 is provided with a plurality of radially extending lugs 9 of which three have been shown in the drawings and these are provided with threaded openings for the reception of the cap screws 10 which extend through openings in ring 4 and serve to hold the motor in place. When the motor is mounted in the manner shown and above described, it will be held very securely in such a position that its shaft will be concentric with the ring 1 and any sounds or noises produced by the ball or roller bearings will be prevented from reaching the ring 1 and the surface on which this is mounted, and therefore they will not be magnified as they otherwise would be if the motor were connected with the ring by metallic means through which the sound waves could be readily transmitted. Secured to the shaft 11 of the motor is a fan. In the example illustrated this fan has been shown as provided with four blades forming two diametrically located pairs spaced ninety degrees apart. The blades are of the aeroplane type as these have been found to move through the air with the greatest efficiency. Although four blades have been shown, it is, of course, possible to employ a smaller or greater number of blades, but with the speed of rotation employed with this type of fan and the moderate diameter of the fans, four blades have been found to operate quite successfully. Fans of this type are intended to force air in the direction of the arrows in Fig. 2 and are usually attached to the end 100

of the cylindrical duct or conduit which has been shown by dotted lines and which has been indicated by reference numeral 12, in Fig. 2. It is apparent that when the fan is in operation that the air pressure on the delivery side will be increased over that on the intake side and therefore there is a constant tendency for the air to flow backwardly from the delivery side to the intake side. Some of this air will return through the space between the outer tips of the fan and the inner surface of ring 1, but as this can be made very small the slippage at this point can be decreased to a very small amount. It is evident that if the fan had only two blades and was rotating at ordinary speed, that there would be a great opportunity for slippage through the opening between the blades, and it has therefore been customary to provide fans of this type with a larger number of blades so as to reduce the tendency for slippage. In the fan illustrated and described the fans have each been provided with a rearwardly extending projection 13 on the following side and near the outer ends. The width of this projection has been calculated so that at the normal rate of speed the time that it takes the fan blades to rotate through ninety degrees minus the angular width of the fan and projection is less than the time necessary for the air to reverse and flow to the other side of the fan and therefore when the fan is rotating at normal speed, there can be no slippage of air between the fan blades near the peripheries as this is prevented by the presence of the lugs or projections 13. There is also another place where air usually flows rearwardly through a ventilating fan and this is a circular space concentric with the axis of rotation. This is due to the fact that at this point the lineal velocity of the blades is much less than at points farther removed from the axis and besides this the fan portion of the blade usually terminates before it reaches the center with the result that there is very little fan action in the zones directly surrounding the axis of rotation, and therefore unless some means is provided to prevent it, air will return from the delivery side to the intake side of the fan in this zone. To prevent slippage around the center of the fan, I have provided the latter with a circular barrier 15 which also serves to connect the root portions of the fans 16. When the fan is provided with a barrier like that indicated by reference numeral 15 and has the following edges of the fans provided with extensions 13, the amount of slippage can be reduced to a negligible quantity without decreasing the efficiency of the fan.

From Figs. 5 and 6 it will be seen that the front surfaces of the parts 13 lie in the plane of rotation and are not intended to assist in propelling the air, but as above

explained, their function is to prevent a return flow of air or slippage at these points. As the fan blades are practically of uniform width and since they rotate at all points along their length at the same angular velocity, it is apparent that there is a greater tendency to slippage near the outer ends of the fan than at any other point along their length, except the center as above described. 70

In the drawings I have shown a plug connector 17 which is secured to the frame and from which a cable 18 extends to the motor. Connection with the power is made by means of a plug 19 and the speed of the motor can be controlled by means of a switch 80 20 which also serves to stop and start the motor. 75

From the above description it will be seen that I have produced a ventilating fan of a simple and substantial construction in which 85 the motor is mounted by a means which serves to deaden the sound and therefore prevent the noises from the bearings from being magnified to any appreciable extent and in which the fan is so constructed that 90 the slippage of air is reduced to a negligible amount without thereby increasing the amount of power per unit of air handled. 95

Having described the invention what is claimed as new is:

A ventilator fan comprising a hub provided with a plurality of narrow fan blades that extend radially from the hub, the front sides of the blades being flat and inclined to the plane of rotation, the rear sides being 100 convex, the outer end of each blade being provided with a tip that extends from one side thereof and which lies substantially in the plane of rotation. 105

In testimony whereof I affix my signature. 110
